F. GERBER.

FAN.

APPLICATION FILED FEB. 5, 1907.

912,464.

Patented Feb. 16, 1909.

UNITED STATES PATENT OFFICE.

FRANK GERBER, OF NEW YORK, N. Y.

FAN.

No. 912,464.

Specification of Letters Patent.

Patented Feb. 16, 1909.

Application filed February 5, 1907. Serial No. 355,876.

To all whom it may concern:

Be it known that I, FRANK GERBER, a citizen of the United States of America, and residing at New York, in the county of New York and State of New York, have invented certain new and useful Improvements in Fans, of which the following is a specification, such as will enable those skilled in the art to which it appertains to make and use the

same.

This invention relates to rotary fans and the object thereof is to provide such a device which is adapted to be used in connection with sewing machines and the like; a further object being to provide a fan of this class which may be readily adjusted to drive air in any desired direction and at any desired altitude within the limits thereof; a still further object being to provide a fan of this class which may be readily thrown out of connection with said sewing machine and entirely out of the way, which is simple in construction and operation and which is comparatively inexpensive.

My invention is fully described in the following specification, of which the accompanying drawings form a part, in which the separate parts thereof are designated by the same reference characters in each of the views, and in which:—

Figure 1 is an end view of a sewing machine with my fan in position thereon; Fig. 2 is a plan view of the fan; Fig. 3 is a section taken on the line 3—3 of Fig. 1; and Fig. 4 is a section taken on the line 4—4 of Fig. 3.

In the drawings forming part of this application, I have shown a sewing machine comprising the table *a*, arm *b* and hand wheel *c* and at the end of the table *a* is hinged, as shown at *d*, a base block *d*², the lower side of which is cut away and a screw *d*³ passed through the block *d*² and which, when rotated, inclines the said block correspondingly. Base block *d*² is of V or wedge-shape and is hinged at its thickest end portion to table *a*.

The base block *d*² is provided with a groove *e* in which moves a lug or tongue secured to a plate *e*² through which passes a screw *e*³ mounted in the base block *d*² and the rotation thereof moves the plate *e*² correspondingly upon the said base block. The plate *e*² carries a standard at one side thereof which is of any desired height and is provided with a vertical groove *e*⁴ in which an upright *e*⁵ is adapted to move and be secured therein by means of a screw *e*⁶ and rotatable in the top

of the upright *e*⁵ is a vertical shaft *e*⁷ which carries a pulley *e*⁸ which is connected with a pulley *e*⁹ on the hand wheel *c* by means of a belt *f* and secured to the plate *e*² is a vertical tube *f*² in which the lower end of the shaft *e*⁷ rotates. Upon the top of the upright *e*⁵ is a circular boss *h*, concentric with the shaft *e*⁷, and rotatable therearound is a collar *h*² which is held in position thereon by means of a disk *h*³ secured to the boss *h* and a thumb screw *h*⁴ serves to lock the collar *h*² to the said boss in any desired position.

The collar *h*² carries a standard *i*³ at one side thereof and through which passes a shaft 70 provided at the outer end with fan blades *i*⁴ and at the inner end with a pinion *i*² enmeshed with a gear wheel *i* secured to the vertical shaft *e*⁷ and it will be seen that when the shaft *e*⁷ is rotated by means of the belt *f* 75 the fan blades *i*⁴ are rotated and the air is agitated and driven thereby, and it will also be seen that this results in any position of the collar *h*² with relation to the boss *h* because of the concentric arrangement and an 80 operator on the sewing machine may therefore direct the air in any desired direction, horizontal, at an incline, or from any height or he may throw the fan entirely out of the way.

Having fully described my invention, what I claim as new and desire to secure by Letters Patent, is:

1. In combination with a sewing machine and its table, a base block of wedge-shape hinged at its thickest end portion to said table, a set screw passing through the opposite end of said base block and resting on said table at its free end, said base block having a groove in its top face, a plate having 90 a tongue slidably arranged in said groove, a vertical standard at one side of said plate, formed with a vertical groove, an upright adjustably mounted in said vertical groove, said upright having a horizontal part at its 95 upper end, a vertical tube secured to said plate at a point adjacent its free end, a shaft slidably fitted in said tube and having its upper end passed through said horizontal part of the upright, a gear on said shaft 100 above said horizontal part, and a fan driven from said gear and arranged on said horizontal part.

2. In combination with a sewing machine and its table, a plate on the table, a vertical standard carried by said plate, a vertical tube also carried by said plate and spaced

from said standard, an upright adjustably secured to said standard, said upright having a horizontal top which projects outwardly, a shaft having one end slidably 5 mounted in said tube and having its opposite end passed through said horizontal top of the upright, a fan on said top, and means carried by the shaft for operating said fan.

3. In combination with a sewing machine 10 and its table, a plate arranged on said table, a vertical standard carried by the plate, an upright secured to said standard, said upright having a horizontal top portion, a shaft projected through said top portion and carry- 15 ing a gear wheel on its upper end, a collar ro-

tatably mounted on said horizontal top of said upright, a vertical standard carried by said collar, a short horizontal shaft carried by said standard of the collar, a gear wheel on said short shaft meshing with said gear wheel 23 of the first named shaft, and a series of fan blades on the opposite end of said short shaft.

In testimony that I claim the foregoing as my invention I have signed my name in presence of the subscribing witnesses this 25 fourth day of February, 1907.

FRANK GERBER.
